(57) **CLAIM**

The ornamental design for an aerodynamic drag reduction device for a trailer, as shown.

DESCRIPTION

FIG. 1 is a front perspective view of the aerodynamic drag reduction device for a trailer of this invention;

FIG. 2 is a top view of the aerodynamic drag reduction device for a trailer of this invention;

FIG. 3 is a left side view of the aerodynamic drag reduction device for a trailer of this invention;

FIG. 4 is front view of the aerodynamic drag reduction device for a trailer of this invention;

FIG. 5 is a bottom view of the aerodynamic drag reduction device for a trailer of this invention;

FIG. 6 is a right side view of the aerodynamic drag reduction device for a trailer of this invention; and,

FIG. 7 is a rear view of the aerodynamic drag reduction device for a trailer of this invention.
